Fig. 3.

Patented Mar. 20, 1928.

UNITED STATES PATENT OFFICE.

WILLIAM MEYER, OF CHICAGO, ILLINOIS.

HOLDER FOR MANICURE PREPARATIONS AND THE LIKE.

Application filed November 26, 1926. Serial No. 150,854.

This invention relates to a holder for manicure preparations and the like.

The invention is not limited, however, to a particular use but may be employed as a theatrical make-up box, for example, and for various other purposes.

While it has been found desirable to make the bodies of devices of this sort of glass, a glass structure has made it difficult to provide a suitable cover for the device. Where the device is circular in form, with the cover fitting over the top of the device, and free to turn or rotate thereon, I find that turning or rotation of the cover smears the contents of the compartments from one to another. This is objectionable as the mixing of the contents, or preparation, in one compartment with that in another compartment, in this manner, may render both preparations useless for their intended purposes.

The smearing of the contents over the top of the container also leaves smudges and accumulations upon the top of the container between the compartments which give an untidy appearance and will interfere with the proper fitting of the cover upon the container.

It is the object of the present invention to provide a simple structure in the way of a unitary body, preferably of glass, and having a plurality of compartments or wells, and to provide a body of this sort with a cover held against turning or rotation so that there is no smearing or smudging of the contents of the compartments, the cover being adapted to be opened to uncover all of the wells or compartments at the same time.

This is advantageous because in a single manicuring operation it is frequently necessary to use all of the preparations and independent opening of the various wells may therefore be objectionable.

It is a feature of the invention that I provide an improved hinge connection between the holder or body of the device and the cover, which permits hinging the cover to the device even though same is formed of glass and which permits swinging the cover upwardly from the top of the container and down into closed position thereon. The structure of the cover permits it to be raised slightly from the margin so that it will not come into contact with the preparations in the wells when closed.

The invention as illustrated in the accompanying drawing in which:

Figure 1 is a plan view of a container embodying the present invention showing the cover and its hinged connection to the container in horizontal section on the line 1, 1 of Fig. 2;

Fig. 2 is a vertical sectional view taken on the line 2, 2 of Fig. 1; and

Fig. 3 is a vertical section taken on the line 3, 3 of Fig. 2 to the hinged connection between the cover and the container.

The body of the device is in the form of a cylindrical block 5, preferably of glass. The glass block 5 is provided with a plurality of relatively small radially elongated wells 6, two relatively large circular wells 7 and with a central relatively deep well 8. The well 8 is disposed on the axis of the block 5 with the wells 6 and 7 spaced substantially equi-distantly, circularly or circumferentially thereabout and with all wells opening from the top of the block 5 and closed at the bottom.

The central relatively deep well is adapted for holding cotton while the larger wells 7 are adapted for holding liquid or other preparations which are used in greater quantities or more rapidly than the other preparations which may be placed in the wells 6.

The glass block 5 has an integral generally rectangular glass boss 10 projecting radially therefrom. The upper surface of the boss 10 is flush with the upper surface of the block 5 and its depth is sufficient to provide a good solid mounting for the posts to which the cover is hinged and not as great as the depth of the block 5 so that the lower ends of the posts may extend below the same without interfering with the bottom supporting surface of the block 5.

A cover 12 preferably of sheet metal or the like fits upon the top of the block 5. The cover 12 is circular in form and conforms substantially with the circular top of the block 5. It has a down turned marginal edge or flange 13 which fits down over the top of the block 5 and adjacent to the boss 10, the cover 12 has an integral radially extending strip or tab 14.

Passing vertically through the boss 10 are a pair of openings 16 and secured in the boss 10 through these openings are the cover mounting posts 18. The upper ends of the posts 18 are headed as at 20 to form

shoulders which engage the top of the boss 10. The shanks of the posts 18 pass through the openings 16 and are threaded at 21 for threaded engagement with nuts 22 which are brought up against washers 23 interposed between them and the bottom of the boss 10 and firmly secure the posts 18 in the boss 10. Suitable washers 24 may be interposed between the heads 20 of the posts, 10 and the top of the boss 10.

The heads 20 may be finished to give a finished appearance to the device and each head 20 has a lateral opening 25 for receiving the opposite ends of a cross pin 26 upon which the cover is hinged by turning or rolling the integral tab or strip 14 thereof around the pin 26 at 28. The opposite ends of the pin 26 fit rotatably in the openings 25 and the width of the tab 14 is substantially equal to the distance between the heads 20 to fit therebetween and by its end-wise cooperation with the heads 20 to hold the cover against longitudinal displacement along the pin 26.

25 The rolling of the tab or strip 14 around the pin 26 forms an effective hinge knuckle and the cover is thereby effectively hinged to the glass block 5. In assembling the device the rolled knuckle 28 of the cover may be placed upon the pin 26, the opposite ends of the pins 26 inserted in the openings 25 in the heads of the posts 18 and the shanks of the posts 18 inserted through the openings 16 and secured in the boss 10 by the nuts 22.

30 The cover 12 may be raised centrally at 30 from the margin 32 so that the margin only will cooperate with the margin of the top of the block 5 and the cover 12 will not come into contact with the preparations in the wells of the block 5 when the cover is closed.

35 In using the device the cover 12 is swung upwardly about the pin 26 as a pivot and opens or uncovers all of the wells 6, 7 and 8 at the same time and making the preparations therein all accessible for use. When the manicure or other use to which the preparations are put is finished the cover 12 is swung down upon the top of the block 5 and closes all of the wells at the same time without smearing the contents of one well to another or smudging or musing the top of the container. The raising of the cover at 30 removes it from contact with the preparations in the wells when it is closed and the hinge connection provided between the container and the cover permits hinging the cover to the container even though same is formed of glass.

60 The extension of the opposite ends of the pin 26 into the heads at the upper ends of the posts 18 holds these posts firmly against relative rotation when the device is assembled.

I claim:

1. In a device of the class described, the combination of a body of glass having an integral boss extending laterally from the side of the body and having a plurality of wells in the body, said boss having a pair of openings vertically therethrough, a pair of posts headed at their upper ends and having shanks passing down through said openings and engaging in nuts below the boss, 70 the headed upper end of each of said posts having a lateral opening therein, a cross pin having its opposite ends engaging in said openings, a sheet metal cover fitting over the top of the body for covering and uncovering said wells, an integral sheet metal tab extending laterally from said cover and rolled back upon said pin, said cover being held in covering position upon the top of said body solely by the rolling of said tab 80 around said pin and the fit of the tab between the headed upper ends of said posts, said cover having a depending marginal flange adapted to fit over the body when the cover is closed, and the top of said cover being raised so that it will not come into contact with the contents of the wells when the cover is closed.

2. In a device of the class described, the combination of a body of glass having an integral boss extending laterally from the side of the body and having a plurality of wells in the body, said boss having a pair of openings vertically therethrough, a pair of posts headed at their upper ends and having shanks passing down through said openings and engaging in nuts below the boss, the headed upper end of each of said posts having a lateral opening therein, a cross pin having its opposite ends engaging in said openings, a sheet metal cover fitting over the top of the body for covering and uncovering said wells, an integral sheet metal tab extending from the margin of said cover and rolled back around said pin, 100 said tab being of an overall width equal to the distance between the headed upper ends of said posts along said pin and said cover being held in covering position upon the top of said body solely by the rolling of said tab around said pin and the fit of the tab between the headed upper ends of said posts, said cover being raised centrally so that it will not come into contact with the contents of the wells when the cover is closed.

3. In a device of the class described, the combination of a body having an integral boss extending laterally from the side of the body and having a plurality of wells in the body, said boss having a pair of openings vertically therethrough, a pair of posts headed at their upper ends and having shanks passing down through said openings and engaging in securing means below the

boss, the headed upper end of each of said posts having a lateral opening therein, a cross pin having its opposite ends engaging in said openings, a sheet metal cover fitting over the top of the body for covering and uncovering said wells, an integral sheet metal tab extending from the margin of said cover and rolled around said pin, said tab being of an overall width substantially equal to the distance between the headed up-

per ends of said posts along said pin and said cover being held in covering position upon the top of said body by the rolling of said tab around said pin and the fit of the tab between the headed upper ends of 15 said posts.

In witness whereof, I hereunto subscribe my name this 23 day of November, 1926.

WILLIAM MEYER.
